DESIGN FOR A BASE FOR A DISPLAY STANDARD

Harry A. Silvers, Beverly Hills, Calif.

Application February 18, 1939, Serial No. 83,093

Term of patent 3½ years

To all whom it may concern:

Be it known that I, Harry A. Silvers, a citizen of the United States, residing at Beverly Hills, California, in the county of Los Angeles and State of California, have invented a new, original, and ornamental Design for a Base for a Display Standard of which the following is a specification, reference being had to the accompanying drawing, forming a part thereof.

Figure 1 is a top plan view of a base for a display standard showing my new design.

Figure 2 is a side elevational view thereof.

I claim:

The ornamental design for a base for a display standard, as shown.

HARRY A. SILVERS.
